UNITED STATES PATENT OFFICE.

DUDLEY JAMES BARNARD, OF BARKING, ENGLAND.

GRAB.

Application filed March 7, 1924, Serial No. 697,657, and in Great Britain March 14, 1923.

The present invention relates to improvements in and relating to grabs of the type in which all movements of the grab are usually effected by a single chain or rope.

5 It is frequently found necessary with grabs of large capacity to discharge the contents in different places without dumping and without the use of an additional chain or rope and the present improvements have for 10 their object the provision of means for enabling the bucket sections of the grab to be partly opened to discharge part of the contents, closed, and opened and closed again as often as desired until the bucket is empty, 15 without dumping the grab.

It is proposed to attain the objects of this invention by the provision of means on the head of the grab adapted to be automatically actuated by certain moving parts of the grab 20 and to coact with a tipping ring suspended from the jib of the crane.

In the accompanying drawings which illustrate this invention:—

Figure 1 is a side elevation of a grab 25 partly in section with the buckets in the closed position, the load being supported by the hauling chain.

Figure 2 is a front elevation thereof.

Figure 3 is a front elevation partly in 30 section showing the buckets in a partly opened position, the load being supported by the tipping ring.

Figure 4 is a similar view partly in section showing the buckets in the fully opened 35 position.

Figure 5 is a side elevation, on an enlarged scale, of the head of the grab illustrating that part of the mechanism adapted to co-operate with the tipping ring.

40 Figure 6 is a section on line 6—6 of Figure 5.

Figure 7 is a similar view showing the parts in another position.

45 Figures 8, 9, and 10 are similar views to Figures 5, 6 and 7 respectively of a modification, and.

Figures 11, 12 and 13 are similar views to Figs. 5, 6 and 7 respectively of a further modification.

50 In order that certain parts of the mechanism forming the subject of this invention may be more clearly illustrated, the dash pot and part of one of the spreader arms have been removed in Figures 1, 3 and 4.

55 In the drawings, 1 and 2 are the bucket sections pivoted on independent pins 3 and 4

on a cross-beam 5, 6 and 7 are the top cross bars and 8 the spreader arms, one being arranged at each corner of the bucket sections. The means for maintaining the normal balance of the operative parts of the grab consists of two vertically disposed telescopic devices arranged one on each side of the sheave blocks, one member 9 of each device being carried by the top cross bars 6 and 7, the other member 10 of each device being carried by the cross-beam 5. Each of the members 9 and 10 pass through sleeves or thimbles 11 and 12 carried by the lower sheave block plates 13 and 14.

70 The mechanism adapted to co-operate with the tipping ring is illustrated on an enlarged scale in Figures 5, 6 and 7 modifications thereof in Figures 8 to 13.

According to the construction illustrated 75 in Figures 5 to 7 the sheave block plates 15, 16 carried by the top cross bars 6, 7 are provided on each side with a pair of brackets 17 to the upper part of each of which is pivoted a hook shaped element 18 the upper ends of 80 which are adapted to coact and engage with a tipping ring 19 (Figures 1, 3 and 4) suspended from the jib of the crane. The lower end of each of the elements 18 is furnished with a projection 20 adapted to enter recesses 21 provided in the weight elements 22 slidably arranged between the brackets 17. The elements 22 are maintained in position by pins 23 secured in the brackets 17, said pins passing through slots 24 provided in 85 the elements 22 the length of such slots determining the rise and fall of the elements 22.

The lower ends of the elements 22 are adapted to coact with buffers 25 provided on the lower sheave block plates 13, 14.

90 When the grab is supported by the hauling chain 26, and the gravity catches 27 are in the locking position as shown in Figure 1, there is a space between the upper face of the lower sheave block and the lower face 100 of the upper sheave block so that the elements 22 are free to fall into their lowest position and the weight thereof is such that they maintain the upper ends of the hook shaped members in their innermost position 105 (Figures 2 and 6). When it is desired to discharge the contents of the grab, the hauling chain is drawn in so as to raise the grab up to the tipping ring 19. The weight of the ring is such that it will force the hook shaped elements 18 outwardly against the pull of the weight elements 22 until the

hooks are past the flange on the ring when the hooks will again be drawn inwardly. If the hauling chain is now paid out the entire load will be carried by the ring and the 5 grab buckets may be opened and closed as desired so as to discharge the contents at different points so long as the gravity catch 27 is maintained in its locked position, that is, in engagement with the pin 28 carried 10 by the cross beam 5. When it is desired to completely open the bucket sections the hauling chain is paid out to an extent which will cause the outwardly extending arm of the catch 27 to engage with the part 29 provided on the lower end of an arm 30 pivoted at 31 to the block plate 15, which thereby causes the disengagement of the catch 27 and the bucket sections fall into the position shown in Figure 4. The upper end of the 15 arm 30 is so shaped that it coacts with a part 32 mounted on the top cross bar 6 which limits the swinging movement of said arm.

When it is desired to free the grab from 25 the tipping ring, the hauling chain is drawn in and the lower sheave block raised to its highest position so as to bring the buffers 25 into engagement with and raise the weight elements 22, a slight further upward movement 30 of the grab releases the hooks from the ring and they fall outwardly as shown in Figure 7. The grab may now be lowered free from the ring on to the material to be raised and closed in the usual manner.

35 In the modified form of mechanism illustrated in Figures 8, 9 and 10, the hook shaped elements 18 are pivoted in the brackets 17 on pins 33, the elements 18 being so shaped and provided with weights 34, 35, 40 that their upper hook shaped ends always fall inwards towards the centre as shown in Figure 9, except when the bucket sections are fully opened and the lower sheave block plates 13 and 14 are in their highest position, 45 as shown in Figure 10. In this form of construction the buffers 25 on the lower sheave block plates are preferably arranged to extend outwardly and upwardly as shown so that as the lower block is raised towards 50 the upper block, the lower ends of the elements 18 and of the weights 34 are gradually forced inwardly until the upper hook shaped ends are forced outwardly out of engagement with the ring 19.

55 In the modified form of construction illustrated in Figures 11, 12 and 13, the hook shaped elements 18 are shaped similarly to those shown in Figures 5, 6 and 7 but the projections 20 on the lower ends thereof 60 are caused to engage with recesses 36 provided in the upper ends of rods 37 slidably arranged in lugs or guides 38, 39 provided on the block plates 15 and 16 and located between the brackets 17 supporting the elements 18. The lower end of each of the

65 rods 37 is provided with a collar 40 between which and the guide 38 is located a spring 41 which serve to maintain the rods 37 in their lowermost position and said rods are arranged to extend below the bottom of the 70 upper block plates 15, 16 and to coact with buffers 25 provided on the lower block plates 13, 14.

75 What I claim is:—

1. In a grab of the single chain type having a cross-beam, movable sheave block, means for connecting the cross-beam and sheave block and a tipping ring, the combination of devices located at the head of the grab adapted to coact with said tipping ring, means carried by the said movable sheave block adapted to move said devices out of engagement with and out of the path of said tipping ring and means pivoted to the head of the grab adapted to coact with the means connecting the cross-beam and sheave block to effect the complete opening of the grab.

80 2. In a grab of the single chain type having a cross beam, a movable sheave block, means connecting the cross beam and sheave block, brackets, a tipping ring, the combination of a pair of hook-shaped elements pivoted in said brackets and lying in the path of the tipping ring, buffers on said movable sheave block, means connected to said hook-shaped elements adapted to coact with said buffers for moving said elements 85 out of engagement with and out of the path of said tipping ring, and a depending arm pivoted to the head of the grab adapted to engage with and effect the disengagement of the means connecting the cross beam and movable sheave block.

90 3. In a grab of the single chain type having a sheave block and plates therefor, a tipping ring, a lower sheave block and plates therefor, and a cross beam, the combination of two pairs of brackets secured one on each side of the upper sheave block 95 plates, a pair of oppositely disposed hook-shaped elements pivotally mounted in said brackets and adapted to engage with said tipping ring, means located between the brackets on the upper block plates, means 100 carried by the lower sheave block plates adapted to coact with said last named means to control the movements of the hook-shaped elements according to the relative position 105 of the lower block plates with respect to the upper block plates, a gravity catch pivotally mounted on the lower block plates, means provided on said cross beam with which said gravity catch engages, and means pivotally 110 mounted on the upper block plates adapted 115 to coact with said gravity catch to withdraw same from engagement with the means 120 on said cross beam.

125 4. In a grab of the single chain type having a cross beam, a movable sheave block,

- means connecting said cross beam and movable sheave block, upper sheave block plates, a tipping ring, a lower sheave block and plates therefor, the combination of two pairs 5 of brackets secured one on each side of the upper sheave block plates, a pair of oppositely disposed hook-shaped elements pivotally mounted in said brackets and adapted to engage with said tipping ring, means located 10 between the brackets on the upper block plates connected with said hook-shaped elements, means carried by the lower sheave block plates and cooperating with said last named means to control the movements of 15 the hook-shaped elements according to the relative position of the lower block plates with respect to the upper block plates, and means carried by the grab adapted to effect the disengagement of the means connecting 20 the cross beam and movable sheave block.
5. In a grab of the single chain type having a cross beam, a movable sheave block, means connecting said cross beam and block, upper sheave block plates, a tipping ring, a 25 lower sheave block and plates therefor, the combination of brackets secured at the sides of the upper sheave block plates, hook-shaped elements pivoted to said brackets for engagement with said tipping ring, means 30 connected to said elements and located between the brackets on the upper block plates, and means carried by the lower sheave block plates for coacting with said last named means to control the movements of the hook-shaped elements according to the relative 35 position of the lower block plate with respect to the upper block plates.
6. In a grab of the single chain type, the combination of an upper sheave block, 40 brackets secured thereto, hook-shaped elements pivoted in said brackets, a tipping ring for engagement by said elements, a lower sheave block, cooperating means on the upper and lower sheave blocks for controlling the movements of the hook-shaped 45
- elements according to the relative position of the lower block with respect to the upper block, a gravity catch pivoted on the lower block, a cross beam provided with a pin for engagement by said catch, a depending arm 50 having a limited swinging movement pivotally mounted on the upper block, said gravity catch having an extending arm to cause disengagement of the catch from the pin on the cross beam. 55
7. In a grab of the single chain type, the combination of a pair of hook-shaped elements, brackets on the grab in which said elements are pivoted, a tipping ring for engagement by said elements, a movable sheave 60 block, buffers on the movable sheave block adapted to move said elements out of engagement with and out of the path of said tipping ring, a gravity catch carried by the sheave block, bucket sections, a cross beam 65 to which said bucket sections are pivoted, said cross beam having a pin for engagement by the gravity catch, and a depending arm having a limited swinging movement pivoted on the upper sheave block adapted 70 to engage with and move said gravity catch out of engagement with the pin.
8. In a grab of the single chain type having a cross-beam, a movable sheave block, means for connecting the cross-beam and 75 sheave block, brackets in the head of the grab, a tipping ring, the combination of a pair of hook-shaped elements pivoted in said brackets and adapted to lie in the path of and to engage with said tipping ring, means on said movable sheave block adapted to move said hook-shaped elements out of engagement with and out of the path of said tipping ring, and means having a limited 80 swinging movement and pivoted to the head 85 of the grab and adapted to engage with and effect the disengagement of the means connecting the cross-beam and movable sheave block.

DUDLEY JAMES BARNARD.
